UNITED STATES PATENT OFFICE.

EDWARD L. ANDERSON, OF ATTLEBORO, MASSACHUSETTS.

SNAP-FASTENING.

1,211,810.

Specification of Letters Patent.

Patented Jan. 9, 1917.

Application filed April 25, 1916. Serial No. 93,378.

To all whom it may concern:

Be it known that I, EDWARD L. ANDERSON, a citizen of the United States, residing at Attleboro, in the county of Bristol and State 5 of Massachusetts, have invented a new and useful Improvement in Snap-Fastenings, of which the following is a specification.

This invention relates to certain new and useful improvements in snap fastenings, capable of use with cuff buttons of the separable type, garments, gloves, and the like.

The primary object of the invention is to provide a snap fastening of simple and economical structure involving minimum of 15 parts and material.

In the drawings—Figure 1 is a side elevation of a cuff button with the present invention applied thereto. Fig. 2 is a plan view of the male member of the cuff button. Fig. 3 is a similar view of the female member. Fig. 4 is a view similar to Fig. 1, partly broken away and in section. Fig. 5 is a plan view of the locking disk, and Fig. 6 is a sectional view of the invention for 25 use as a garment fastening or the like.

As shown in Figs. 1-4, the invention is applied to a cuff button in which the heads 1 and the shanks 2 are similar. The male member has the usual head 3 secured to a 30 disk 4, which latter has its edge rolled over the flared end of the shank 2 as shown at 5.

The female member is provided with a locking disk 6 having radial cut-outs 7 emanating from a common cut-out center, forming 35 a series of thin spring fingers 8 engageable with the neck of the head 3. A disk 9 having a central opening 9' engages the locking disk 6 and has its edge at 10 rolled over the flared end of the shank 2, securing the locking disk between this flared 40 end and the disk 9. For the purpose of providing fulcrum for the spring arms 8 the disk 9 is provided with an annular out- 45 struck rib 11 which is common to all of the spring fingers or arms 8 and engages the latter at points between their ends as depicted in Fig. 4, of the drawings. This provides means which enables the spring fingers to readily respond to the in move- 50 ment and obstruct out movements of the head 3, by holding the fingers spaced from the disk 9. By reference to Fig. 4, it will be seen that there is space between the parts of the fingers 8 which rest on the rib 11 and

the flared end of the shank which provides 55 for free movement of the fingers in responding to the in movement of the head 13.

In Fig. 6 a fastening especially for use in connection with garments or the like is shown, and in which the male member has 60 a disk 12 provided with a head 13 and the female member has a disk 14 provided with the circular rib 15, the female member having a top 16 secured by the rolled edges 17 of the base disk 14. The locking disk has 65 the spring fingers 18, all of the parts where similar or corresponding to those above referred to being identical with the same parts described in Figs. 1-5 of the drawings.

In cuff buttons, the two parts 1, 1, are 70 passed through the buttonholes of the two ends of the cuff and then the male member 3 is snapped into engagement with the female member, while in garment uses, the usual manner of affixing the members by 75 sewing or otherwise is followed.

Having thus described my invention, what I claim as new and desire to secure by Letters Patent is—

1. In a snap fastening, a male member 80 having a head and a female member having a base disk formed with a head-receiving opening, said base disk being formed with a struck-out rib disposed approximately central between its periphery and said opening, 85 and a locking disk secured at its periphery adjacent the periphery of the base disk and having a series of spring fingers to engage the head, said rib engaging the fingers at points approximately central of the length 90 of the fingers and holding same entirely out of contact with the base disk, and approximately parallel to the base disk whereby upon outward movement of the head the fingers will be moved thereby through the 95 space between the fingers and the base disk before engaging the latter.

2. In a snap fastening, a male member having a head and a female member having a base disk formed with a head-receiving opening, said base disk being provided with a narrow inwardly extending rib located approximately central between its periphery and said opening, and a locking disk 100 secured at its periphery adjacent the periphery of the base disk and having a series of spring fingers to engage the head, said rib 105 engaging the fingers at points approxi-

imately central of the length of the fingers and holding same entirely out of contact with the base whereby upon outward movement of the head the fingers will be moved thereby through the space between the fingers and the base disk before engaging the latter.

In testimony whereof I have signed my name to this specification in the presence of two subscribing witnesses.

EDWARD L. ANDERSON.
